Fred G. Detenbeck
ATTORNEYS

UNITED STATES PATENT OFFICE.

HARRY BEAUREGARD ROSS, OF DENVER, COLORADO.

WASHING MACHINE.

Original application filed May 13, 1921, Serial No. 469,198. Divided and this application filed November 7, 1922. Serial No. 599,553.

To all whom it may concern:

Be it known that I, HARRY B. Ross, a citizen of the United States, residing at Denver, in the county of Denver and State of Colorado, have invented a new and Improved Washing Machine, of which the following is a specification.

My present invention has for its object to provide certain new and useful improvements in washing machines and the present invention has especially for its object to provide certain new and useful improvements in the pounders employed in such machines.

In my application Serial No. 469,198, filed May 13, 1921, I have disclosed an improved washing machine in which the present invention is especially adapted for use and the present application is a divisional part of my original application Serial No. 469,198 aforesaid. In such original application I have disclosed a washing machine which comprises generally a tub or reservoir for the water in which is rotatably mounted a perforated washing and drying cylinder and on the edge of which tub is mounted a support that sustains the power mechanism for turning the cylinder and also for operating the crank shaft on which the pounders are located.

In my present application I make no claim to the construction of the washing machine as a whole as that constitutes the subject matter of my original application, the present application being confined to the pounder construction per se.

It is therefore an object of my present invention to provide a pounder in the nature of a vacuum cup device for engaging the fabric to effect the surging of the same in the vessel in which the treatment occurs so as to force air and suds through the fabric and thereby effect the cleansing action.

In its generic nature, my present invention comprises a vertically movable rod to the lower end of which is secured a rubber vacuum cup, there being an outer vacuum cup slideable on the rod and adapted to receive the rubber cup.

In the drawing Figure 1 is a central vertical section, parts being in elevation, showing my invention in use in connection with the washing machine of my original application aforesaid.

Figures 2 and 3 are detail vertical sections illustrating the action of the vacuum cup members.

In the drawings in which like numerals of reference indicate like parts in all of the figures, 1 is the tub or tank which is mounted in any suitable way on any suitable base or support 2 and in which the combined washing and drying cylinder 3 is mounted for rotation on a vertical axis.

4 represents the support for the crank shaft 5 to which the vertical pounder rods 6 are pivoted as at 7. The rods swing loosely on their pivots and carry the rubber vacuum cups 8 which are attached to the lower ends of the rods.

Enclosing the cups 8 are metallic cups 9 which have sleeves 10 to slide freely up and down on the rods 6.

In using the invention water is placed in the tank 1. The water level should not be above the bottom edge of the rim of the tank so that the cups 8 when at the upward limit of their stroke, will be out of the water and thus enable air to flow into the cups at the end of the up stroke of the plunger rod 6. After the water has been brought to the proper level, the cups are then set straight down into the cylinder 1 on top of the clothes and power is applied to turn the crank shaft 5, thus working the cups 8 and 9 up and down by the action of the cranks.

It will be observed that by my construction of vacuum cups, the neck of the outer metallic cups, sliding freely on the rod 6, in cooperation with the rubber suction cups 8, allows the cups to give to tightly packed clothes or any obstruction to the stroke of the cranks; also air trapped can escape through the loose neck 10, then when the cranks are on the upward stroke, the metallic cups remain down until the rubber piston cups 8 move up until an air tight connection between the cups 8 and 9 is effected, thereby intensifying the vacuum which pulls the suds through the clothes rapidly and is quite a practical improvement over the common simple vacuum cups heretofore used in washing machines of this general type.

From the foregoing description taken in connection with the accompanying drawing, it is thought the complete construction, operation and advantages of my invention will be readily understood.

What I claim is:

1. In apparatus of the class described, a vacuum cup clothes working member comprising a rod, a rubber vacuum cup on the end of said rod, an outer vacuum cup slid-

able on said rod and enclosing said rubber cup said rubber cup being adapted, when said outer cup is in the lowermost position to effect a securing engagement with the 5 same, substantially as shown and described.

2. In apparatus of the class described, a vacuum cup clothes working member comprising a rod, a rubber vacuum cup on the end of said rod, an outer vacuum cup slid- 10 able on said rod, and enclosing said rubber cup, said rubber cup being adapted when said outer cup is in the lowermost position to

effect a sliding engagement with the same, substantially as shown and described.

3. In apparatus of the class described, a 15 vacuum cup clothes working member comprising a rod, an inner vacuum cup on the end of said rod and an outer vacuum cup slid- 20 able on said rod and enclosing said inner cup, said inner cup adapted, when said outer cup is in the lowermost position, to effect engagement with the same, substantially as shown and described.

HARRY BEAUREGARD ROSS.
